UNITED STATES PATENT OFFICE.

HYMAN KLEINBERG, OF BROOKLYN, NEW YORK.

HAT AND METHOD OF MAKING SAME.

Application filed February 1, 1929. Serial No. 336,862.

This invention is an improvement in the manufacture of cloth hats, the main objects being to produce a soft hat which will not shrink upon getting wet, which is devoid of 5 visible seams, will hold its shape, will not be injured by any ordinary bending or folding, and will present an attractive appearance.

As important features of my improved construction the outer layer or surface portion 10 of the crown of the hat is formed of a single piece of textile fabric which is stretched to the proper form and firmly secured to the inner layer by an intermediate layer of waterproof material. The brim is independently 15 formed of separate layers of textile fabric with intermediate stiffening and waterproofing material.

In the accompanying drawings there is 20 illustrated one embodiment of my invention and certain of the parts employed in the construction thereof.

In these drawings:

Fig. 1 is a perspective view of the completed hat, the outer ribbon or band being 25 omitted;

Fig. 2 is an inside view of the crown;

Fig. 3 is a vertical section through the crown on the line 3—3 of Fig. 2;

Fig. 4 is a perspective view of the crown;

Fig. 5 is a plan view of the superposed layers employed in making the brim, portions 30 thereof being broken away;

Fig. 6 is a transverse section on the line 6—6 of Fig. 5;

Fig. 7 is a section similar to Fig. 6, showing the outer edge of the brim after the application of the binding strip, and

Fig. 8 is a section on the line 8—8 of Fig. 1, but on a greatly enlarged scale.

In the manufacture of the crown there is 40 first formed the inner layer or body which is preferably of felt but may be of other textile material. It may be a blown body of felt or may be stretched to the proper form, or may be made up of sections of the proper size and shape and secured together.

As shown in Figs. 2 and 3, the inner layer 10 of the crown is made up of a top piece 10^a and two strips 10^b sewed together along an 50 upper annular seam, and two side seams. This inner layer is fitted over a wooden block of appropriate form and is caused to accurately fit this block by pressing and stretching if needed.

Over this inner layer there is then stretched 55

a layer 11 of rubber tissue which will completely cover the inner layer and lie smooth thereon. The outer layer 12 of the crown is then applied. It is preferably formed from a single piece of woven fabric which is laid over the top of the crown and carefully worked and stretched down over the sides of the crown until it completely and accurately fits all portions of the outer surface of the layer of rubber tissue. This working and 60 stretching of the cloth will be comparatively easy if the cloth be loosely woven, but can be accomplished even if the cloth be of comparatively close weave or if it be of some other kind of textile fabric. The intermediate and 65 outer layers are held in stretched condition by any suitable retaining means, as for instance a tight cord around the lower end of the block over which they are stretched, and the entire structure is then heated to soften 70 the rubber tissue and cause it to adhere to the inner end outer layers. Preferably the outer layer is ironed or pressed in by hand to cause a firm contact with the rubber tissue throughout the entire area. Thereafter the crown is 75 removed from the block and is trimmed around the lower edge to produce a construction substantially as shown in Figs. 2, 3 and 4.

A sizing strip 13 is secured to the inner surface of the crown of the proper length depending upon the size of the hat. This strip is of inelastic material and when the ends thereof are secured together and the strip is secured against the inner surface of the crown it prevents any stretching of the crown 85 and holds it to the definite predetermined size. A binding strip 14 of substantially inelastic material is then secured around the lower open end of the crown, to enclose the edges of the layers and the edge of the sizing 90 strip, and to give to the crown a finished appearance. If desired, a layer of rubber tissue 95 is employed on the inner surface of the binding.

In forming the brim there are employed 100 two layers 15 and 16 of cloth, a layer 17 of canvas or other stiffening material, and two layers 18 and 19 of rubber tissue. The intermediate layer 17 may be of burlap, duck, 105 felt, or other material. The two layers of cloth are preferably of the same character as that used to form the outer layer of the crown, and in assembling the various layers to make up the brim, the two layers are placed together as shown in Figs. 5 and 6. A bind- 110

ing strip 20 is then sewed to the outer edge of the brim, as shown in Fig. 7. This binding is of inelastic material, rubberized on the inner surface, and in attaching it the main 5 layers may be contracted somewhat so as to facilitate the later forming of the roll or upturn of the outer edge of the brim. Thereafter the upper cloth layer 15 is folded around the binding strip 20 into engagement with 10 the lower rubber tissue layer 19, and the entire brim is heated and pressed in molds of the proper form to give the curl to the brim and to permanently connect all of the layers. The layer 15 is originally cut of slightly larger 15 diameter than the other layers to facilitate the folding around the outer edge and both cloth layers may be made of slightly less inner diameter than the intermediate stiffening layer to provide a comparatively flexible inner edge formed only with upper and lower cloth layers 16 and 15 which may be sewed to the inner surface of the crown, as shown in Fig. 8. After the attaching of the brim to the crown the usual leather sweat band 21 20 may be secured in place, and any form of ribbon or band (not shown) may be applied around the lower outer portion of the crown.

In my improved construction the upper 30 surface of the brim, the under surface of the brim, and the outer surface of the crown are each formed of a single piece of material. They are each secured to a stiffening or reinforcing layer by adhesive which in itself forms a waterproof layer so that the stiffening 35 layer cannot become wet from rain or snow, and therefore will not shrink and will hold the outer cloth layers against shrinkage even though the latter be of woolen cloth or other material which would tend to shrink 40 when wet. Both the crown and brim are of sufficient stiffness to retain the desired form but may be bent or folded in any manner without injury to the hat. The hat has a very much more attractive appearance than 45 the ordinary form of cloth hat in which the crown is formed of separate sections connected by a plurality of seams.

Having thus described my invention, what

I claim as new and desire to secure by Letters Patent is:

1. The method of making a hat crown which includes forming the inner layer of the desired shape, rigidly supporting it from the interior, applying a layer of a waterproof adhesive material to the outer surface, forming an outer layer by stretching a single piece of woven textile fabric to fit the top and sides of the crown, applying an inelastic sizing strip to the surface of the crown adjacent to its lower open edge, and applying a binding around the lower edge of the crown and the lower edge of said strip. 50

2. The method of making a hat crown which includes forming an inner layer of the desired shape, rigidly supporting it from the interior, applying thereto a layer of rubber tissue, forming an outer layer by stretching a single piece of woven fabric to conform to the top and sides of the crown, heating and pressing the superposed layers with the outer layer in stretched condition to cause the rubber tissue to adhere to both layers, trimming the outer edge, securing an inelastic sizing strip to said edge, and securing a binding strip to enclose the lower edges of said layers 60 and said strip. 65

3. The method of forming a hat brim which consists in securing together two layers of woven cloth, a layer of stiffening material and adhesive upon the upper and lower surfaces 70 of the layer of stiffening material, securing a binding strip around the outer edge, folding the upper cloth layer around the binding strip into engagement with the adhesive at the lower surface of the stiffening layer, and 75 pressing said layers together. 80

4. A hat crown including inner and outer layers of textile fabric, an adhesive therebetween, a sizing strip at the lower edge, and a binding enclosing the said edge and the 85 edge of said strip. 90

Signed at New York, in the county of New York and State of New York, this 30th day of January A. D. 1929.

HYMAN KLEINBERG.
